KNOP YARN AND METHOD OF MAKING
THE SAMEEdwin Bry, Elberon, N. J., assignor to Edwin &
Louis Bry, Inc., New York, N. Y., a corporation
of New York

Application November 13, 1940, Serial No. 365,400

5 Claims. (Cl. 57—144)

My invention relates to a novelty yarn and a novel process of making the same and more particularly my invention relates to a yarn comprising a multiplicity of decorative threads twisted over a core in such a fashion that each decorative thread forms a multiplicity of adjacent knobs, the multiplicity of decorative threads forming a distinct set of knobs with a repeat pattern along said yarn.

The most important considerations in the manufacture of the novelty yarn are to obtain distinct novelty effects and at the same time to get a reasonably light yarn so that it is not too costly and so that it can be used in a variety of fabrics.

In the novelty yarn of my present invention I obtain variegated effects in the form of a repeat pattern which is made up of a multiplicity of knobs, as for example two adjacent knobs, formed from a single decorative thread and a multiplicity of decorative threads, such as for example five, being used to form a series of 10 knobs for each repeat pattern, the ten knobs being formed two each from the five different decorative threads.

The method of making my novelty yarn is such that an extremely light decorative yarn is obtained especially with regard to the variegated decorative effect obtained by the use of a multiplicity of decorative threads.

It is the object of my invention to provide a novelty yarn having variegated effects in a repeat pattern.

It is a further object of my invention to provide a novelty yarn made up of a series of different and distinct decorative threads.

It is a further object of my invention to provide a novelty yarn which has as its primarily decorative motif a series of a plurality of knobs of a multiplicity of decorative threads.

It is a further object of my invention to provide a novel method of twisting about a core a plurality of decorative threads so that each decorative thread forms two adjacent knobs, the decorative thread being then twisted about the 45 yarn until the knob pattern is repeated.

These and further objects of my present invention will be apparent from a consideration of the drawing and the specific description thereof which here follows:

Figure 1 is a perspective of the novelty yarn of my invention.

Figure 2 is a side view of the apparatus employed in forming the novelty yarn of my invention.

Figure 3 is a front view of the apparatus which illustrates the method of forming the novelty yarn of my invention.

Figure 4 is a detail showing the stage in the process of the manufacture of my novelty yarn next after that shown in Figure 2.

Referring now more specifically to the drawing, in Figure 1 I show a novelty yarn generally denoted as 10, which comprises two knobs 11 and 12 formed from a thread of decorative material 13 which may, for example, be rayon. Immediately adjacent the two knobs 11 and 12 of decorative material 13, are knobs 15 and 16, formed from a second decorative material 17, which knobs may be, for example, of worsted.

Knobs 19 and 20 formed from decorative material 21 are positioned adjacent knobs 15 and 16. After knobs 19 and 20 come knobs 22 and 23 which are formed from still another thread of decorative material 24 which may be, for example, worsted. Seen at the extreme right of Figure 1 are knobs 26 and 27 formed from a thread of decorative material 28 which may be, for example, worsted.

25 The knobs aforementioned are twisted over a suitable core which, as shown, is made up of two threads 42 and 43, of, for example, cotton or the like. The novelty yarn is bound back with the binder 31.

30 The various decorative threads employed preferably are distinct and different from one another and particularly the respective sets of adjacent knobs, such as knobs 15 and 16 are distinct in appearance and in contrast with knobs 19 and 20. It will be recognized that the knobs 11 and 12 are similar to one another and are formed from the same thread of decorative material 13, and similarly knobs 15 and 16 are formed from the same thread of decorative material 17.

40 The threads of decorative material employed may be rayon, worsted, wool, silk, mohair or any suitable decorative material, and the pattern in which five different decorative threads are employed as shown in Figure 1 is repeated along the yarn as will be more particularly pointed out hereinafter.

In Figure 2 I have shown an apparatus comprising suitably mounted reels 40 and 41 from which are drawn core threads 42 and 43. The core threads 42 and 43 are drawn between idler roll 45 and the driven roll 46. Roll 46 has a sprocket 47 shown in dotted line mounted on 55 one end thereof and this sprocket 47 is driven

by pins 48, 49 etc. mounted on the driven wheel 50.

By means of this driven pin and idler sprocket arrangement, an intermittent motion is effected in the roll 46. Core 42, 43 moves downwardly and about this core are twisted the decorative threads 13, 17, 21, 24 and 28 which are drawn from suitable mounted rolls 57, 58, 59, 60 and 61. The decorative threads which, as above, may be threads of rayon, worsted, wool, silk, mohair or any suitable decorative material are drawn by the continuously moving set of rolls made up of idler roll 64 and driven roll 65. The threads 13, 17, 21, 24 and 28 of decorative material pass over faller bars 70, 71, 72, 73 and 74, respectively, and form knobs over the core 42, 43. The knopped yarn 10 which is formed then passes through the guide 76 and through the traveller 77 and thence is wrapped around the driven bobbin 78.

The method of my invention is as follows:

The core 42, 43 is moved downwardly in intermittent motion by the pins 49 on the wheel 50 so that the core stops in front of the faller bars 70-74 and after a predetermined period during which knobs 11, 15, 19, 22 and 26 are formed on the core by the threads of decorative material 13, 17, 21, 24 and 28, the core again moves down a short space at which time, as shown more particularly in Figure 4, the knobs 12, 16, 20, 23 and 27 are formed adjacent to the first formed knobs, so that a pattern of ten knobs, each two of which are similar and formed from the same decorative thread, are formed over the core 42, 43. The two adjacent knobs being of the same decorative material and therefore the same color and appearance form a novelty yarn having a multi-color effect in which, for example, areas of blue, gold, red, green and white forming a repeat pattern, occur in regular sequence.

After the two knobs such as 11 and 12 are formed from the thread of decorative material 13, and similarly the other knobs are formed from other threads of decorative material, the pins 48, 49 etc. by reason of the rotation of the wheel 50 engage the sprocket 47 and turn the roll 46 for a sufficient length of time to move the knopped yarn down completely beyond the faller bars and to bring a new portion of the core 42-43 into position by the faller bars 70-74 so that another set of knobs can be formed on that portion of the yarn.

By means of the process above set forth, I employ a minimum of decorative thread material and the decorative thread may be light in weight because of the combination of threads involved so that I obtain a distinctive novelty yarn which is extremely light in weight, reeling as for example in the case of the use of four decorative threads of worsted and one decorative thread of rayon, about 962 yards of novelty yarn to the pound. It will be realized that this is light weight novelty yarn and hence of definite value.

It is to be understood that it is within the purview of my invention to form a multiplicity of adjacent knobs of the same decorative material. That is, in lieu of the two knobs of the same dec-

orative material, as shown in the present specific example of my invention, I may employ three, or four or even more adjacent knobs of the same material. I may also employ more or less than the five decorative threads shown and I intend to include such variants in the decorative threads employed in the present invention.

The sets of adjacent knobs formed of the same decorative thread, and therefore presenting the same appearance characteristics, make for a general color patch appearance in the novelty yarn.

Certain variations in the method of manufacture will be apparent to those skilled in the art. It is my intention, therefore, not to be limited by the particular examples of the yarn and method of making the same which I have set forth by way of specific example of my invention, but only by the claims hereto appended.

I claim:

1. A novelty yarn comprising a multiplicity of threads of decorative material twisted about each other, a multiplicity of knobs formed from each thread of decorative material, at least two knobs formed from the same decorative material being positioned adjacent one another.

2. A novelty yarn comprising a multiplicity of threads of decorative material twisted about a core, and a multiplicity of knobs formed from each thread of decorative material, at least two knobs formed from the same decorative material being positioned adjacent one another.

3. A novelty yarn comprising a multiplicity of threads of decorative material twisted about a core, at least two adjacent knobs being formed in said yarn from each thread of decorative material, said yarn being characterized therefore by a multiplicity of sets of knobs of decorative material along its length.

4. A novelty yarn comprising a multiplicity of threads of decorative material twisted about a core, at least two adjacent knobs being formed in said yarn from each thread of decorative material, said yarn being characterized therefore by a multiplicity of sets of knobs of decorative material along its length, each set of knobs contrasting in appearance with the next adjacent set of knobs.

5. The method of forming a novelty knob yarn comprising advancing a core, stopping said core, twisting a multiplicity of spaced threads of decorative material about said core to form knobs thereon, advancing said core again a relatively short distance, again stopping said core, twisting the same multiplicity of spaced threads of decorative material about said core to form a second set of knobs about said core adjacent to but spaced from said first set of knobs, said second set of knobs being formed from the same threads of decorative material respectively as said first set of knobs, and moving said core a relatively longer distance so that said multiplicity of spaced threads of decorative material can form sets of knobs about another area of said core.

EDWIN BRY.
